CORPORATION OF DELAWARE.

ACCOUNT-FINDING MACHINE.

Application filed November 8, 1920. Serial No. 422,658.

This invention relates to machines for finding accounts.

In the account finding machine described in applications Serial Number 229,996, filed April 22, 1918, and Serial Number 352,601, filed January 19, 1920, now Patent No. 1,615,806 of Jan. 25, 1927, and also in British Patent No. 158,344, November 2, 1920, the account cards are arranged in a tray (or a series of trays) and a desired account is found by primary location of a group of cards, secondary location of a division or unit of cards, and a tertiary location of a card, and the finally located card is then isolated. This is accomplished by providing selecting mechanism which is set by selective manipulative means comprising a series of keys so as to effect such selection.

After a desired account or accounts has or have been found and isolated by such location and elevation of the selectors, the selecting mechanism is restored to clear the machine by operation of a crank. This, however, requires the manual operation of the crank after each account has been found. Accordingly, where a series of cards in a tray are desired successively, an undue amount of labor is required for the successive clearings of the machine.

One of the objects of this invention, therefore, is to provide a machine whereby the selecting means will be automatically restored and more particularly whereby the restoring of the selecting means is accomplished upon and after an interval following the setting of the selecting means.

In order to audit the accounts, auditing mechanism is employed as distinguished from the normal selecting mechanism, which is arranged to locate and isolate a series of cards, one in each unit, so as to not only check up the system, but also find lost or misplaced accounts. It is desirable, however, when auditing, to render the automatic restoring of the selecting means ineffective, especially since during auditing a series of cards, one hundred in number, is isolated by auxiliary isolating means which

is manually operated and, therefore, manually restored.

Another object of this invention, therefore, is to provide means for rendering the automatic restoring of the selecting means ineffective when desired, and more especially during auditing of the accounts.

Further objects will appear from the detail description taken in connection with the accompanying drawings, in which:

Figure 1 is a detail side elevation of so much of the mechanism of the account finding machine of the application referred to as is pertinent to this invention;

Figure 2 is a detail front elevation, showing the automatic restoring mechanism embodying this invention;

Figure 3 is a rear elevation;

Figure 4 is a side elevation of Figure 2;

Figure 5 is a plan of Figure 4;

Figure 6 is a detail view taken about on line 6-6, Figure 2; and

Figure 7 is a detail, somewhat reduced, showing the motor connection.

In the different views, parts have been omitted; this has been done to promote clearness, for if all the parts particularly relevant were shown, it would obscure the particular mechanism under consideration.

Referring more particularly to Figure 1, which shows so much of the mechanism of the machine described and shown in the application referred to as will render its operation clear, 1 designates the base of the machine which is provided with suitable side members 2 and brackets 3 and 4 so as to provide a frame for the mechanism. A carriage 5 comprising a pair of side members is arranged for transverse movement on tracks 6 on the frame, it being understood that this carriage is supported at both ends in a similar manner. Mounted upon this carriage are the side members of a carrier 7 on which are vertically movable the normal selectors S and audit selectors or bars P. The carrier 7 is arranged for longitudinal shifting movement on the carriage and is retained by latches 8. This carrier also sup-

ports shafts 9 provided with clutches 10 for selectively clutching the shafts to a desired pair of selectors S. It will be understood that springs are provided for moving all of the parts.

5 Mounted above the selectors is a tray 11 having partitions 12 dividing the tray into a series of compartments, each of which is arranged to receive a series of ten cards C 10 provided with variant tabs along their lower edges corresponding respectively to the positions of the cards in a compartment.

A series of normal keys 13 are provided, these being ten in number, and as there are 15 three locations in order to finally locate a desired card, a shiftable transmitter carrier 14 is provided to transmit the movements of the keys to the mechanisms for controlling the primary, secondary and tertiary operations of the selectors. The primary or group 20 selection of the selectors is obtained by clutching a pair of selectors with the shafts 9 and for this purpose, the plungers 15 in the transmitter carrier are arranged to co- 25 operate with a series of latches 16 which normally retain the levers 17 connected by links and arms with and for operating the clutches 10. The secondary location is obtained by shifting the carrier 7 rearwardly the required 30 number of spaces which is accomplished by a series of stops 18 cooperating with a cross-bar 19 on the carrier and controlled by latches 20 from the keys 13 through the plungers 15. The tertiary location 35 is obtained by moving the side members of the carriage 5 inwardly, this being accomplished by the release of a latch 21 co-operating with a cross bar 22 connected with the carriage and cooperating with a series of 40 variable stops 23 controlled by a series of elements 24 from the keys 13 operating through the medium of the plungers.

After final location, the shafts 9 are rotated upon release of the latches 25 and 26 45 cooperating with a lug 27 on a link 28 connected with these shafts in the manner shown in said Patent No. 1,615,806.

For instance, in order to obtain card # "122," as shown in Figure 1, the auditor 50 will depress successively keys "1," "2" and "2." Upon the primary depression of the "1" key, the "1" selectors S will be clutched with the shafts 9; upon secondary depression of the "2" key, the carrier 5 will be moved 55 forward and located in position to align the "1" selectors S with the "20" compartment; upon tertiary depression of the "2" key, the selectors will be moved inwardly to align the "1" selectors in the "20" compartment 60 with the tabs on the "2" card. Upon rotation of the shafts 9, the "2" card will now be elevated.

In order to restore the mechanism to normal position, the following mechanism is 65 provided. The link 28 is connected with a

bell-crank lever 29 having a roll 30 cooperating with a cam 31 connected by a link 32 with an arm 33 on a rock shaft 34 provided with an arm 35 connected by a link 36 with an arm 37 of a bell crank lever loose on a 70 rock shaft 38, the other arm 37 being connected with the cross head 19, as shown in Patent No. 1,615,806. Segments 58 and 59 fixed to the ends of the shafts 38 and 39 mesh and connect these shafts, and shaft 38 75 is provided with a crank 39. An arm 40 is also fixed to the rock shaft 34 and is connected by a link 41 with the bar 22. There are similar connections to the other mechanisms, the result being that upon moving 80 the crank 39 in the direction of the arrow, Figure 1, the parts will be restored to normal position with the selectors in normal or "0" position.

The audit selectors P are arranged to be 85 interconnected with the normal selectors S by a shift bar 42 operated by the audit key 89 as shown in Patent No. 1,615,806 and manually operative means are provided for then raising all of the selectors. For this 90 purpose, the rock shaft 38 has loosely mounted thereon an arm 43 connected by a link 44 with a lever 45 arranged to take behind the pin connecting the link 28 with the bell-crank lever 29. Accordingly, upon tripping 95 of the latches 25 and 26, the selectors may be raised manually by moving the arm 43 in the direction of the arrow, Figure 1.

As described in the applications referred to, the depression of keys will release the 100 different mechanisms so that under the action of the springs, the primary, secondary and tertiary locations will be rendered. A motor is, however, provided for restoring the mechanisms, (see application Serial 105 Number 229,996) this motor being attached to the base 1 and its shaft being shown at 46 and a clutch is provided between the motor and the rock shaft 38, which clutch has an element 47 having a helical outer periphery including a shoulder 47^a engaged by a stop 48 connected to a lever 49 pivoted at 50 on the base and connected by a link 51 with an arm 52 on a shaft 53 having an arm 530 connected in turn by a lever 54 with a tripping bar 55, a spring 56 being provided for normally holding the stop 48 down. The shoulder 47^a corresponds to the pin 404 in application Serial No. 229,996, and British Patent No. 153,344 and serves substantially 110 the same purpose. Accordingly upon depression of the tripping bar 55, release of the shoulder 47^a and element 47 will cause the motor to be clutched to the actuating 115 rock shaft 38 so as to restore the mechanism.

It is to be understood that where such motor mechanism is provided, the crank 39 can be omitted.

The mechanism so far described is fully 120

described in the disclosures referred to and further description is, therefore, unnecessary, it being noted that the motor which is normally in motion will, upon actuation of the tripping bar or upon movement of the lever 49, be connected with the actuating rock shaft 38 so as to clear the machine.

It will be noted that after final location of the selecting mechanism and upon tripping of the latches 25 and 26 causing release and therefore actuation of the shafts 9 to elevate the located selecting mechanism, the bell-crank lever 29 is moved about its pivot so as to cause the lever arm thereof and the cam 15 roll 30 on this lever arm to be elevated.

Referring now to Figures 2 to 5 inclusive, slidably mounted on the bracket 3 is a shifting bar 60 having a cam portion 61 cooperating with a cam roll 62 on the pin connecting the stop 48 and the lever 49. This bar is slotted at 63 and the slot is engaged by a stud 64 on a cross-head 65 provided with a stud 66 moving in a guide slot 67 in a bracket 68 mounted on the base. This cross-head is connected with a spring 69 anchored on the base. The cross-head is provided with a beveled lug 70 in the path of the toe 71 on an arm 72 pivoted on a bracket 73 attached to the bracket 3 and having the free end 74 thereof in the path of the cam roll 30 on the bell-crank lever 29. A spring 75 connects the arm 72 with the bracket 3 and normally tends to hold this arm down against a stop 760 on the bracket 73.

Upon elevation of the located selectors, when the bell crank lever 29 is moved by the cam 31 (during operation of the resetting lever 39), the cam roll 30 will strike against the free end of the arm 72 and move the toe 71 thereof out of the path of the lug 70 thereby permitting the spring 69 to move the bar 60 forward and cause the cam 61 thereon by engagement with the roll 62 to elevate the stop 48 so as to release the clutch and permit the motor to restore the mechanisms and clear the machine. Accordingly upon final location and isolation of a card, the selecting mechanism will be automatically restored.

Now it is desirable that there be a time interval between the isolation of a card and the restoring of the mechanism in order to permit the card to be examined and in order to insure that all parts will be finally located. In accordance with this invention, therefore, retarding means is provided so as to provide an interval following such setting of the selecting mechanism, after which the selecting mechanism is restored. Accordingly, the cross-head 65 has attached thereto the stem 76 of a plunger 77 working in a cylinder 78 pivoted in a bracket 79 on the base so as to form a dash pot. This dash pot is, however, provided at its side with a port 80 open to the air and arranged to be uncovered

by the plunger. A regulating valve 81 may further be provided to initially regulate an aperture in the end of the cylinder.

Upon release of the cross-head, the movement thereof will be retarded by the reduction of pressure below atmospheric pressure in the dash pot cylinder and the resultant retarding effect of the external atmospheric pressure. This retardation will continue until the plunger 77 passes the port 80 at 78 which time atmospheric pressure will be re-established inside of the dash pot. Accordingly, the first movement of the cross head will be a slow one succeeded by a quick movement. The slow movement is for the purpose of providing a time interval after the setting of the selecting mechanism, while the quick movement serves to release the clutch and permit the motor to restore the selecting mechanism. This interval may be varied by adjustment of the valve 81 so as to suit requirements.

When auditing, it is desirable that the automatic restoring mechanism be rendered ineffective, for at this time, the period of inspection is unusually long. Accordingly, mechanism is provided for this purpose. The clutch-shifting bar 60 has a lug 82 arranged to be engaged by a latch 83 pivoted at 84 on the bracket 3 and having an arm 85 provided with a face 86 cooperating with a pin 87 on a bar 88 connected with the audit key 89. A spring 90 connected with the arm 85 and anchored on the bracket 3 tends to hold the face 86 against the pin 87 and this arm is also provided with a recess 91. Upon depression of the audit key 89, the pin 87 will move down along the face 86 until it drops into the recess 91 whereupon the spring 90 will swing the latch 83 and cause it to take behind the lug 82 on the shifting bar 60 so as to prevent clutching of the clutch when the selectors are raised for auditing purposes. Accordingly, during auditing, the automatic restoring mechanism is rendered ineffective. The mechanism, however, is restored upon depression of the tripping bar 55 and accordingly in order to again restore the automatic mechanism, the link 51 is connected with a lever 92 pivoted on the bracket 3 and provided with a pin 93 adapted to engage the arm 85 and shift this arm back so as to raise the latch and release the bar 60 and also to permit the audit bar to be again raised by its spring.

When the mechanism is restored by the motor, the automatic mechanism is also restored. For this purpose, the arm 40 has a pin and slot connection with a link 94 pivoted on the stud 64. Accordingly, when the arm 40 swings to the left, Figure 4, in clearing the machine, it will, after a limited movement (sufficient to take up the lost motion between the cross head and the link 94) return the cross head to normal posi-

tion, the beveled lug 70 engaging the toe 71 on the arm 72 and permitting this toe to again drop behind the lug so as to latch the parts in normal position.

5 It will, therefore, be seen that this invention accomplishes its objects. In accordance with this invention, upon setting the normal selectors to locate and isolate a card, the mechanism will after final location and 10 isolation be restored for subsequent operation. The provision of the retarding mechanism, however, causes a time interval after such final location and isolation so as to permit inspection and complete action before 15 the mechanism is restored. Accordingly it is not necessary for the auditor to depress the tripping bar after the location of each card. When auditing, however, the automatic mechanism is rendered ineffective, but 20 this mechanism is again rendered effective after the machine has been restored through the medium of the tripping bar or any other means.

In the specification and the claims, the 25 term "card" is used in its broadest sense so as to cover ordinary loose leaves, cards, sheets and other accounting elements.

It is obvious that various changes may be 30 made in details of description without departing from the spirit of this invention; it is, therefore, to be understood that this invention is not to be limited to the specific details shown and described.

Having thus described the invention, what 35 is claimed is:

1. A machine of the character described, comprising, card selecting means, means for setting said selecting means, and means for automatically restoring said selecting means.

40 2. A machine of the character described, comprising, card selecting means, means for setting said selecting means, and means operating upon such setting for restoring said means.

45 3. A machine of the character described, comprising, card selecting means, means for setting said selecting means, and means for restoring said selecting means after an interval.

50 4. A machine of the character described, comprising, card selecting means, means for setting said selecting means, and means operating automatically upon such setting adapted to restore said selecting means.

55 5. A machine of the character described, comprising, card selecting means, means for setting said selecting means, and means operating automatically after an interval following such setting adapted to restore said selecting means.

60 6. A machine of the character described, comprising, card selecting means, selective manipulative means for setting said selecting means, and means for automatically restoring said selecting means.

7. A machine of the character described, comprising, selecting means selective manipulative means for setting said selecting means, and means operating automatically upon such setting adapted to restore said 70 selecting means.

8. A machine of the character described, comprising, card selecting means, means for setting said selecting means, means for restoring said selecting means, and means 75 for automatically actuating said restoring means.

9. A machine of the character described, comprising, card selecting means, means for setting said selecting means, means for restoring said selecting means, and means operating 80 upon such setting adapted to actuate said restoring means.

10. A machine of the character described, comprising, card selecting means, means for setting said selecting means, means for restoring said selecting means, and means operating at an interval after such setting adapted to actuate said restoring means.

11. A machine of the character described, comprising, card selecting means, means for setting said selecting means, means for restoring said selecting means, and means for retarding said restoring means.

12. A machine of the character described, comprising, card selecting means, means for setting said selecting means, means for restoring said selecting means, means for actuating said restoring means, and means for retarding said actuating means.

13. A machine of the character described, comprising, card selecting means, means for setting said selecting means, means for restoring said selecting means, and means operating after a time interval after such setting for automatically actuating said restoring means.

14. A machine of the character described, comprising, card selecting means, means for setting said selecting means, means for restoring said selecting means, and means operating automatically after setting of said selecting means adapted to actuate said restoring means.

15. A machine of the character described, comprising, card selecting means, selective manipulative means for setting said selecting means, means for restoring said selecting means, and means for automatically actuating said restoring means.

16. A machine of the character described, comprising, card selecting means, means for setting said selecting means, means for restoring said selecting means, and actuating means for said restoring means, controlled 125 by said setting means.

17. A machine of the character described, comprising, card selecting means, means for setting said selecting means, means for restoring said selecting means, an actuator for 130

said restoring means, and a controller for said actuator.

18. A machine of the character described, comprising, card selecting means, means for setting said selecting means, means for restoring said selecting means, an actuator for said restoring means, and a controller for said actuator governed by said setting means. 5

19. A machine of the character described, comprising, card selecting means, means for setting said selecting means, means for restoring said selecting means, an actuator, and means operated upon such setting adapted to connect said restoring means with 10 said actuator. 75

20. A machine of the character described, comprising, card selecting means, means for setting said selecting means, means for restoring said selecting means, an actuator, 20 and means operated at a time interval after such setting adapted to connect said restoring means with said actuator. 80

21. A machine of the character described, comprising, card selecting means, means for setting said selecting means, means for restoring said selecting means, an actuator, means for connecting said restoring means 25 with said actuator, and means for retarding such connection. 85

30 22. A machine of the character described, comprising, card selecting means, means for setting said selecting means, means for restoring said selecting means, an actuator, means controlled by said setting means for 35 connecting said restoring means with said actuator, and means for retarding such connection. 90

40 23. A machine of the character described, comprising, card selecting means, means for setting said selecting means, means for restoring said selecting means, a motor, a clutch between said motor and said restoring means, and means for automatically shifting 105 said clutch. 100

45 24. A machine of the character described, comprising, card selecting means, means for setting said selecting means, means for restoring said selecting means, a motor, a clutch between said motor and said restoring 110 means, and means controlled by said setting means for shifting said clutch. 110

50 25. A machine of the character described, comprising, card selecting means, means for setting said selecting means, means for restoring said selecting means, a motor, a clutch between said motor and said restoring means, means for shifting said clutch, and means for retarding said shifting means. 115

60 26. A machine of the character described, comprising, card selecting means, means for setting said selecting means, means for restoring said selecting means, a motor, a clutch between said motor and said restoring means, and means for shifting said clutch 125 at a time interval after such setting. 125

27. A machine of the character described, comprising, card selecting means, means for setting said selecting means, means for restoring said selecting means, a motor, a clutch between said motor and said restoring 70 means, and means operating upon such setting for shifting said clutch. 70

28. A machine of the character described, comprising, card selecting means, means for setting said selecting means, means for restoring said selecting means, a motor, a clutch between said motor and said restoring means, clutch-shifting means controlled by 75 said setting means, and means for retarding said shifting means. 80

29. A machine of the character described, comprising, card selecting means, means for setting said selecting means, means for automatically restoring said selecting means, and means for rendering said automatic 85 means ineffective. 85

30. A machine of the character described, comprising, selecting means, means for setting said selecting means, means for automatically restoring said selecting means, manually controlled means for restoring said selecting means, and means for rendering 90 said automatic means ineffective. 90

31. A machine of the character described, comprising, card selecting means, means for setting said selecting means, means for operating upon such setting for restoring said selecting means, and means for rendering 95 said last means ineffective. 95

32. A machine of the character described, comprising, card selecting means, means for setting said selecting means, means operating at an interval after such setting for restoring said selecting means, and means for rendering said last means ineffective. 100 105

33. A machine of the character described, comprising, card selecting means, means for setting said selecting means, means for operating upon such setting for restoring said selecting means, means for rendering said last means ineffective, and manually controlled means for restoring said selecting 110 means. 110

34. A machine of the character described, comprising, card selecting means, means for setting said selecting means, means for restoring said selecting means, means for automatically controlling said restoring means, and means for rendering said controlling 115 means ineffective. 115

35. A machine of the character described, comprising, card selecting means, means for setting said selecting means, means for restoring said selecting means, means for effecting actuation of said restoring means upon such setting, and means for rendering said last means ineffective. 120 125

36. A machine of the character described, comprising, selecting means, means for setting said selecting means, means for restor- 125

- ing said selecting means, means for effecting actuation of said restoring means at an interval after such setting, and means for rendering said last means ineffective.
37. A machine of the character described, comprising, card selecting means, means for setting said selecting means, means for restoring said selecting means, means operable by said setting means for effecting actuation of said restoring means, means for rendering said last means ineffective, and means for manually effecting actuation of said restoring means.
38. A machine of the character described, comprising, card selecting means, means for setting said selecting means, means for restoring said selecting means, means operable by said setting means for effecting actuation of said restoring means, means for rendering said last means ineffective, and means for manually effecting actuation of said restoring means, adapted to again render said means effective.
39. A machine of the character described, comprising, card selecting means, means for setting said selecting means to locate a card, means for restoring said selecting means, and means for automatically effecting operation of said restoring means.
40. A machine of the character described, comprising, card selecting means, means for setting said selecting means to locate a card, means for restoring said selecting means, and means operating automatically after such location for effecting operation of said restoring means.
41. A machine of the character described, comprising, card selecting means, means for setting said selecting means to locate and isolate a card, and means operating automatically after such isolation for effecting operation of said restoring means.
42. A machine of the character described, comprising, card selecting means, means for primarily and secondarily setting said selecting means to locate a card, means for restoring said selecting means, and means operating automatically after the final setting for effecting operation of said restoring means.
43. A machine of the character described, comprising, card selecting means, means for primarily, secondarily and tertiary setting said selecting means to locate a card, means for restoring said selecting means, and means operating automatically after the final location for effecting operation of said restoring means.
44. A machine of the character described, comprising, card selecting means, means for setting said selecting means to locate a card, means for setting said selecting means to locate a series of cards, and means for automatically restoring said selecting means when set to locate a card.
45. A machine of the character described, comprising, card selecting means, means for setting said selecting means to locate a card, means for setting said selecting means to locate a series of cards, and means for automatically restoring said selecting means after locating a card.
46. A machine of the character described, comprising, card selecting means, means for setting said selecting means to locate a card, means for setting said selecting means to locate a series of cards, means for automatically restoring said selecting means when set to locate a card, and manually controlled means for restoring said selecting means when set to locate a series of cards.
47. A machine of the character described, comprising, card selecting means, means for setting said selecting means to locate a card, means for setting said selecting means to locate a series of cards, means for automatically restoring said selecting means, and means for rendering said automatic means ineffective when said selecting means is set to locate a series of cards.
48. A machine of the character described, comprising, normal card selecting means, audit selecting means, means for setting said selecting means, and means operating upon setting of said normal selecting means for restoring the same.
49. A machine of the character described, comprising, normal card selecting means, audit selecting means, means for setting said selecting means, means for restoring said selecting means, and means operating upon setting of said normal selecting means for effecting actuation of said restoring means.
50. A machine of the character described, comprising, normal card selecting means, audit selecting means, means for setting said selecting means, and means for automatically restoring said normal selecting means.
51. A machine of the character described, comprising, normal card selecting means, audit selecting means, means for setting said selecting means, means for automatically restoring said normal selecting means, and means for rendering said automatic means ineffective.
52. A machine of the character described, comprising, normal selecting means, audit selecting means, means for setting said selecting means, means for restoring said selecting means, means operating automatically upon setting of said normal selecting means for effecting actuation of said restoring means, and means operating upon setting of said audit selecting means for preventing automatic actuation of said restoring means.
53. A machine of the character described, comprising, normal selecting means, audit selecting means, means for setting said select-

ing means, means for restoring said selecting means, means operating automatically upon setting of said normal selecting means for effecting actuation of said restoring means, means operating upon setting of said audit selecting means for preventing automatic actuation of said restoring means, and

manually controlled means for effecting actuation of said restoring means.
